ATTORNEY

UNITED STATES PATENT OFFICE.

HENRY H. WESTINGHOUSE, OF NEW YORK, N. Y., ASSIGNOR TO THE WESTINGHOUSE AIR BRAKE COMPANY, OF WILMERDING, PENNSYLVANIA, A CORPORATION OF PENNSYLVANIA.

ROTARY PUMP.

Application filed July 8, 1922. Serial No. 573,680.

To all whom it may concern:

Be it known that I, HENRY H. WESTINGHOUSE, a citizen of the United States, residing at New York, in the county of New York and State of New York, have invented new and useful Improvements in Rotary Pumps, of which the following is a specification.

This invention relates to a lubricating system more particularly adapted for lubricating the moving parts of a rotary fluid exhauster or pump.

The principal object of my invention is to provide an improved lubricating system of the above character.

15 In the accompanying drawing; Fig. 1 is a central section of a rotary fluid exhauster embodying my invention; Fig. 2 a section on the line 2—2 of Fig. 1; and Fig. 3 a longitudinal section of the end portion of 20 the exhauster, showing the relief valves.

As shown in the drawing, the exhauster may comprise a cylinder formed of half cylinders 1 and 2 bolted together. The half cylinder 1 is counterbored to receive a bushing 25 3 which is pressed into place and said bushing provides a bearing for a rotatable ring 4.

Mounted in ball bearings 5 at opposite ends of the cylinder and disposed eccentrically of the cylinder, as shown in Fig. 2 30 is a shaft 6 and keyed to the shaft is a rotor drum 7 having radial slots 8 for receiving radially movable blades or vanes 9, said blades being provided with bearing strips 10 adapted to bear against the interior wall 35 of the rotor cylinder. Integral with the pump frame is a casing 11, within which the rotor cylinder is mounted, the open end of the casing being closed by a casing cap plate 12.

40 The casing 11 provides an oil reservoir 13 around the rotor cylinder, in which is contained lubricating oil for lubricating the moving parts of the exhauster. Oil is supplied from the reservoir 13 through a passage 14 and past a regulating valve 15 to a longitudinal bore 16 which communicates with a plurality of passages 17 opening at the bearing surface of the rotor cylinder and also with an annular groove 18 formed in 45 the bushing 3. Spaced ports 19 lead from the groove 18 to the bearing face of the guide ring 4.

The fluid discharge passage 20 from the exhauster cylinder leads to the upper por-

tion of the oil reservoir 13 and is connected 55 to a cylindrical discharge nozzle 21 having its outer end closed by a plug 22. The nozzle 21 is provided with longitudinal slots 23 and oil outlet ports 24 and a hood like baffle plate 25 is mounted over the nozzle, as 60 shown in Fig. 2, to assist in separating oil from the fluid discharged from the exhauster. Relief valves 26 may be provided, which control passages leading to the rotor cylinder, so that if the pressure of oil with- 65 in the rotor cylinder should exceed a predetermined degree, the relief valves will open and allow oil trapped in the rotor cylinder to escape from the cylinder into the oil reservoir 13. 70

Underneath the oil hole 24 at one end of the exhauster, the half cylinder 1 is provided with an oil pocket 27 and underneath the oil hole 24 at the other end is an oil pocket 28 in the half cylinder 2. Leading from the 75 pocket 27 is a passage 29 for supplying lubricating oil to the bearing 5 at one end and a passage 30 supplies oil from pocket 28 to the bearing 5 at the other end of the exhauster. 80

In operation, when the exhauster is running, fluid is exhausted from the system to which the exhauster may be connected by way of the inlet ports 31, the fluid being carried between adjacent blades 5 of the rotor around the rotor cylinder and being discharged through the discharge passage 20 to the discharge nozzle 21. 85

The partial vacuum created by the rotation of the blades 9 is sufficient to cause the 90 atmospheric pressure acting on the body of oil in the reservoir 13 to force oil through the passage 14 and past the valve 15 to the bore 16. Thence oil flows through the passages 17 so as to provide lubrication for the 95 bearing face of the rotor cylinder. Oil also flows into and fills the groove 18, so that oil is then supplied through the ports 19 to the bearing face of the bearing ring 4.

Fluid flowing into the discharge nozzle 100 21 flows out through the slots 23 and impinges on the baffle plate 25, so that oil entrained with the fluid tends to collect on the under face of the baffle plate, and the fluid then passes around the baffle plate and 105 escapes to the discharge pipe 32.

Some of the oil collected on the baffle plate will fall into the pockets 27 and 28

and this oil will then be supplied through the respective passages 29 and 30 to lubricate the shaft bearings 5, 5.

Oil collected on the plate 25 which does not fall into the pockets 27 and 28 will fall back into the oil reservoir 13. Some of the oil entrained in the fluid exhausted will also be separated from the fluid while passing through the discharge nozzle and this oil will flow through the ports 24 into the pockets 27 and 28.

The amount of oil supplied may be regulated by adjusting the regulating pin valve 15.

15 Should an excessive amount of oil collect in the rotor cylinder, the pressure thus created will cause the relief valves 26 to open, so that the pressure is relieved by the escape of oil from the cylinder to the oil reservoir 13.

It will be understood that while the construction has been described as a fluid exhauster, it would also operate as a fluid compressor and in fact may be termed a fluid pump.

Having now described my invention, what I claim as new and desire to secure by Letters Patent, is:—

1. In a rotary fluid exhauster, the combination with a cylinder and a pump rotor in said cylinder for exhausting fluid, of a reservoir containing a body of oil subject to atmospheric pressure and a passage establishing communication from the oil reservoir to the rotor cylinder at a point above the level of oil in the reservoir whereby the oil is raised from the reservoir and supplied to the cylinder by the partial vacuum created by the action of the exhauster.

20 2. In a rotary fluid exhauster, the combination with a cylinder and a pump rotor

in said cylinder for exhausting fluid, of means for lubricating the cylinder and a discharge nozzle mounted in axial alignment with the longitudinal axis of the cylinder for receiving fluid discharged from the exhauster having openings for permitting the outflow of fluid and ports through which oil separated from the fluid and deposited in the nozzle will drain.

45 3. In a rotary fluid exhauster, the combination with a cylinder and a pump rotor in said cylinder for exhausting fluid, of means for lubricating the cylinder, a discharge pipe located adjacent to said cylinder into which the fluid discharged from the cylinder passes and having ports through which oil is separated from the fluid and deposited in the pipe may drain, and means for supplying the drained oil to lubricate 50 moving parts of the exhauster.

65 4. In a rotary fluid exhauster, the combination with a cylinder and a pump rotor in said cylinder for exhausting fluid, of means for lubricating the cylinder, a discharge pipe located adjacent to said cylinder into which the fluid discharged from the cylinder passes and having openings through which fluid escapes from the discharge pipe and ports through which oil separated from the fluid and deposited in the pipe may drain, a baffle plate against 70 which fluid escaping from the discharge pipe impinges, and means for collecting oil deposited from the fluid on the baffle plate and oil drained from the discharge pipe and for supplying said oil to the moving parts of the exhauster.

75 In testimony whereof I have hereunto set my hand.

HENRY H. WESTINGHOUSE.
